KEY CONTAINER

John Joseph Nasser, Kingston, Pa.

Application February 9, 1937, Serial No. 124,904

3 Claims. (Cl. 150—40)

My invention relates generally to key containers, and particularly to key containers devoid of metal parts, and an important object of my invention is to provide key containers of the character indicated which are particularly adapted to be attached to and to contain automobile keys.

Another important object of my invention is to provide key containers of the character indicated which are relatively soft and yielding and will not scratch and rattle when contacted with other objects, such as the instrument panel of an automobile, and which are compact and devoid of any parts or protrusions which could catch in or give discomfort when carried in the pocket.

Other important objects of my invention will be apparent from a reading of the following description taken in connection with the drawings, wherein for purposes of illustration I have shown a preferred embodiment of my invention.

In the drawings:

Figure 1 is a general side elevational view of an embodiment of the present invention showing a key connected thereto and withdrawn for use, and showing in dotted lines the key contained within the container when not in use.

Figure 2 is a horizontal sectional view taken through Figure 1 and looking downwardly.

Figure 3 is a side elevational view of another embodiment of the present invention.

Figure 4 is an opposite side elevational view of Figure 3 cut away to show the position of the tongue.

Figure 5 is a top plan view of Figure 3 with the key removed.

Referring in detail to the drawings, and particularly to Figures 1 and 2 thereof, the numeral 5 generally designates an envelope or pocket made of suitable flexible or semi-flexible material such as leather or the like, and which for convenience is rounded at its bottom as indicated by the numeral 6 and curved at its top as indicated by the numeral 7, the top being open. The pocket or envelope is formed preferably of two matching sections 8 and 9 made of leather or the like which are sewed together at their edges as indicated by the numeral 10 so as to leave the upper edges open to give access to the interior of the envelope.

In one side or section of the envelope, such as the section 9 and at one side thereof near the top are two holes 11 and 12 which are horizontally aligned and which may be joined by a slit or slot 13. Beyond the middle and at the opposite side of the section 9 are two vertically aligned holes 14 and 15 which are substantially equally spaced above and below a horizontal imaginary line

passing through the holes 12 and 11 as clearly shown in Figure 1.

A leather thong 16 or other suitable cord has one end 17 fastened as indicated by the numeral 18 between the sewn edges of the sections 8 and 9 as clearly shown in Figure 2. The opposite end of the thong has formed thereon a triangular or barbed enlarged head 19.

The thong is passed from the inside of the envelope outwardly through the lower hole 15 and then along the outer side of the section 9 and then through the hole 14 to the interior of the envelope. The triangular head 19 is then compressed or folded so as to pass through the hole 20 in the key 21 which is to be carried in the envelope, and the head 19 is then passed through the openings defined by the holes 11 and 12 and the slot 13 to the outer side of the section 9, and then passed between the portion of the thong which engages the outer side of the section 9 between the holes 14 and 15, and such portion of the thong, to the position illustrated in Figure 1, wherein the shoulders or barbs on the face of the head 19 engage the side of the said portion of the thong. With the thong brought taut, the portion thereof between the holes 14 and 15 will securely lock the head 19 and hence the thong in the key retaining position.

To remove a key from the thong, the section 22 of the thong lying between the holes 14 and 15 is pulled out sufficiently to pass the head 19 and then the head is drawn through the opening defined by the holes 11 and 12 and the slot 13, and the head then folded sufficiently to pass through the hole 20 and release the key.

Referring to the embodiment of the invention shown in Figures 3, 4 and 5 there is present the envelope 5a similar to the envelope 5 and in the section 9a thereof are holes 11a, 12a, 14a and 15a which cooperate with the thong in the manner already stated in connection with the above described embodiment of the invention. In the present embodiment of the invention the thong end 18a is attached in a vertical position to the section 9a instead of in a horizontal position as shown in Figure 1 of the drawings.

The upper edge of the section 8a of the envelope 5a is cut straight across as indicated by the numeral 7a instead of being curved as in the embodiment of the invention shown in Figure 1 of the drawings. The upper edge of the section 9a is provided with an elongated tongue 23 which is of a maximum width at its point of attachment to the upper edge of the section so as to form an adequate closure for the upper end 55

of the envelope, but beginning at the point 24 the opposite sides of this tongue are tapered curvedly as indicated by the numeral 25 to terminate in a point 26 which depends above the bottom of the envelope as shown in Figure 4 of the drawings. This tongue has substantially parallel slits 27 and 28 which are vertically arranged to define a tab 29 which is cut out of the tongue 23 and is so placed that when the tongue 10 is in the closed position inserted between the sections 8a and 9a as shown in Figure 4 of the drawings, the upper end of the tab 29 will extend above the upper edge of the envelope and thereby be easily within the grasp of the operator who 15 may by grasping the same withdraw the tongue 23 to an open position to enable extraction of the keys. It is to be observed that the thong 16a together with the key 21a when in the operative position, has reached this position by 20 being passed through the opening which is defined by the separation of the tab 29 from the tongue 23. As indicated in Figure 4 of the drawings more than one key 21a may be connected to the key container and retained within the 25 container while one of the keys is in the operative exposed position, the tongue 23 operating to hold the keys not in use within the container and out of contact with objects with which the envelope might strike.

30 Although I have shown and described herein preferred embodiments of my invention, it is to be definitely understood that I do not desire to limit the application of the invention thereto, and any change or changes may be made in the materials and in the structure and arrangement of the parts, within the spirit of the invention and the scope of the subjoined claims.

What is claimed is:

1. A key container of the character described comprising an envelope of relatively flexible material of nonmetallic character having an access opening, a key retaining thong in the form of a loop passing through the opening in a key and having one leg fastened to the interior of the envelope and having its remaining leg fastened to another portion of the envelope, both legs

passing through said access opening, the second-mentioned leg of the loop being passed outwardly through holes formed in the side of the envelope, the first leg being passed outwardly through a hole formed in the side of the envelope, then across the second leg and inwardly through a hole formed in said envelope, whereby a portion of said first leg retainingly overlies a portion of the second leg. 5

2. A key container of the character described 10 comprising an envelope of relatively flexible material of nonmetallic character, a thong adapted to be passed through an opening in a key and having one end fastened to the interior of the envelope and having its opposite end releasably fastened to the exterior of the envelope to retain the key, and a tongue depending from the upper end of one side of the envelope and into the interior of the envelope and normally retaining the thong and key in the envelope, said tongue being formed with an opening to pass said thong and a key to the exterior of the envelope when said tongue is withdrawn from the envelope. 15

3. A key container of the character described 20 comprising an envelope of relatively flexible material of nonmetallic character a thong arranged to pass through the opening in a key and having one end fastened to the interior of the envelope and having its opposite end passed through the opening in the key and releasably fastened to the exterior of the envelope to retain the key thereon, and a tongue depending from the upper end of one side of the envelope and into the interior of the envelope and normally retaining the key and the thong in the envelope, said tongue being formed with an opening 25 to pass said thong and a key to the exterior of the envelope when said tongue is withdrawn from the envelope, and a tab on said tongue 30 projecting into said opening in the tongue and extending above the tongue when the same is in closed position to afford a handle for withdrawing the tongue from the container. 35
